UNITED STATES PATENT OFFICE.

LAWRENCE W. PENNINGTON, OF READING, PENNSYLVANIA.

DESIGN FOR A BADGE OR SIMILAR ARTICLE.

No. 39,552.

Specification for Design.

Patented Sept. 22, 1908.

Application filed June 18, 1908. Serial No. 439,256. Term of patent 7 years.

To all whom it may concern:

Be it known that I, LAWRENCE W. PENNINGTON, citizen of the United States, residing at Reading, in the county of Berks and State of Pennsylvania, have invented a new, original, and ornamental Design for a Badge or Similar Article, of which the following is a specification, reference being had to the accompanying drawings, forming a part thereof.

In the drawing: Figure 1 is a plan view and Fig. 2 is a perspective view of a badge showing my new design.

The badge is oblong and of irregular outline, its upper edge *a* being substantially

semi-circular, its sides *b* slightly curved outwardly, and the lower edge *c* forming a series of curves and producing a "wave line".

The badge is formed with six perforations of various sizes, one of which, *d*, is considerably larger than the others and of irregular shape.

I claim:—

The ornamental design for a badge or similar article, as shown and described.

LAWRENCE W. PENNINGTON.
